(57) **CLAIM**

The ornamental design for a stopper for a medical guide sheath, as shown and described.

DESCRIPTION

FIG. 1 is a front perspective view of an embodiment of a stopper for a medical guide sheath showing our new design; FIG. 2 is a rear perspective view thereof;

FIG. 3 is a front view thereof;

FIG. 4 is a top view thereof;

FIG. 5 is a rear view thereof;

FIG. 6 is a bottom thereof;

FIG. 7 is a cross-sectional view taken along line 7-7 in FIG. 3;

FIG. 8 is a front perspective view of another embodiment of a stopper for a medical guide sheath showing our new design;

FIG. 9 is a rear perspective view thereof;

FIG. 10 is a front view thereof;

FIG. 11 is a rear view thereof;

FIG. 12 is a bottom view thereof; and,

FIG. 13 is a cross-sectional view taken along line 13 in FIG. 10.

The broken lines shown in the drawings are illustrative purpose only and form no part of the claimed design.

1 Claim, 13 Drawing Sheets
